[57] ABSTRACT

A ski pole of a conventional type is utilized in a manner that special means is mounted accessibly and operatively atop the handgrip for detachably mounting, transporting and supporting photographic camera equipment whereby to in this manner permit the ski pole to be employed in the usual manner while skiing and in addition to serve as a stabilizing, aiming support for the photographic camera equipment when the skier feels called upon to use the same.

6 Claims, 3 Drawing Figures

PATENTED MAY 14 1974

3,810,647

FIG. I

FIG. 2

FIG. 3-

SKI POLE WITH CAMERA MOUNTING MEANS

The present invention pertains to a simple, practical and feasible device which is expressly designed and adapted to enable a user thereof to transport and provide a stable support for photographic camera equipment and which with the equipment in place lends itself to practical and reliable use while skiing.

Stated somewhat more explicitly, the concept has to do with converting a conventional ski pole into a support for photographic camera equipment and to provide other features and advantages.

As is generally well known by persons conversant with the field of endeavor herein under consideration and with the exception of certain children's molded ski poles, all ski poles are constructed in a manner to allow replacement of either the pre-shaped handgrip, strap or both. This result is accomplished by removing the ordinarily employed lag screw which is located at the top of the ski pole and replacing the same with novel camera mounting means and screwing the lag screw component thereof into its intended axially located position.

At present there is no conveniently reliable manner of transporting photographic equipment while one is participating in the sport of skiing. Procedures and practices currently in use are often hazardous and cumbersome and have to do with the conventional camera strap which when skiing downhill may fly out dangerously from the shoulder strap and cause the skier to fall. In certain instances the conventional shoulder strap is provided with an additional cord which is tied around the waist for anchorage. This mode of use requires the skier to untie the second cord which involves the removal of gloves and ski poles and results in the likelihood of losing one or more of the items at hand, and often because of cold hands. In either of the practices mentioned once the camera has been freed unless the skier has brought additional equipment with him, he still lacks means, other than physical, to support the equipment. Because of these and other associated difficulties which need not be dwelled upon there has long existed a need which allows a skier to carry his photographic camera equipment and to at some controllable area to enable him to simply press the pointed lower end of the ski pole into the snow, use the shaft as an upright, and catch hold of the handgrip and steady the attached camera for practical and reliably aimed use.

Although photographic cameras and similar equipment are ordinarily supported atop a stabilizing tripod, single support members have been devised with a view toward enabling one to reliably prop the camera in an advantageous position and to use the same with requisite reliability. For background purposes the reader may, if desired, refer to the camera supporting device disclosed in U.S. Pat. No. 2,636,822 granted to Kathryn B. Anderson. In addition for such guidance as may aid in obtaining further background information attention can be given to Frank E. Hanscom camera support disclosed in U.S. Pat. No. 3,074,338.

An object of the present invention is to structurally, functionally and otherwise improve upon prior art supports and, in doing so, to provide an adaptation which well serves the purposes for which it is intended, may be justly endorsed by manufacturers, retailers and users and which well serves the overall purposes for which it has been devised and successfully used.

Briefly the commonly used lag screw is dispensed with and a unique combination lag screw and stud is used in lieu thereof. The device employed to achieve a desired result is characterized by a cylindrical stud. 5 This stud is provided at a bottom portion thereof with an outstanding flange-type limit stop shoulder. The stud serves to accommodate a knurled locknut which in practice engages the bottom of the photographic camera and assists in mounting the same with reliability and security. An upper end portion of the stud projects 10 above the level of the locknut. That portion below the shoulder is provided with a downwardly tapering lag screw and the junctinal portion at the locale of the limit stop shoulder is provided with a compressibly resilient washer, that is a washer which has a convex bottom side fitting into a concave recess provided therefore in the upper end of the customary molded handgrip.

These together with other objects and advantages 20 which will become subsequently apparent reside in the details of construction and operation as more fully hereinafter described and claimed, reference being had to the accompanying drawings forming a part thereof, wherein like numerals refer to like parts throughout.

25 FIG. 1 is a view in perspective showing a photographic camera in phantom lines and how it is mounted atop the novel mounting means at the upper end of the handgrip, that is a handgrip such as is used on the upper end of the shaft of a conventional ski pole.

30 FIG. 2 is a view on a suitably enlarged scale and which is partly in elevation and partly in section, which brings out the construction of the individual parts and the manner in which they are constructed and cooperatively associated with each other.

35 And FIG. 3 is an exploded perspective view which shows the essential component parts individually and in ready-to-assemble relationship.

40 Referring to the views of the drawing the ski pole is denoted generally by the numeral 4, the shaft thereof being designated at 6. The lower pointed end is provided with the usual basket-type or equivalent guard (not shown). The upper end portion is provided as usual with a screw-threaded socket 8 which in practice 45 serves to accommodate a lag screw such as is commonly used but is replaced by the improved adaptation herein shown and described. The numeral 10 designates a conventionally shaped handgrip the covering of which is denoted at 12 and the upper end of which is denoted at 14 and is provided with a concave recess 16. In normal practice this recess serves to accommodate the headed end of the commonly used lag screw (not shown).

55 The improved device comprises a primary component unitary part which is denoted generally by the numeral 18 in FIG. 3. This part comprises a downwardly tapering properly threaded lag screw 20 which in the arrangement shown is adapted to be screwed into the socket 8 which is provided therefore as shown in FIG. 2. The upper end portion of this unit or component part is fashioned into a machine threaded connector which is designated here as a stud 22. There is a surrounding flange-like shoulder provided at 24. In actual practice that portion of the screw just below the flange or limit stop shoulder is equipped with a compressibly resilient rubber or equivalent washer 26 whose lower convex portion 28 is adapted to be seated in the aforemen-

tioned recess 16 as brought out in FIG. 2. The aforementioned locknut comprises an annular rigid metal or ring-like collar 30 having a knurled anti-slipping marginal edge or peripheral portion 32. The screw-threaded opening 34 at the center thereof is screwed in place on the stud and normally cooperates with the shoulder 24 and is interposed between the bottom 36 of the camera 38 in the manner illustrated. This is to say the nut is operatively mounted on the stud and permits a portion of the stud to project above the same to the level shown in FIG. 2 where it is screwed into a flanged fitting or mount 40 provided therefor as shown in phantom lines in FIG. 2.

The invention also features an appropriate cap nut 42 (FIG. 3) and which comprises a cap portion 44 and a nut portion 46.

The illustration appearing in FIG. 2 shows the invention and how it is satisfactorily inserted in place of the customarily employed lag screw. Thus the lag screw in the improved construction denoted at 20 screws into the socket 8 and serves to position and hold the hand-grip 10 and also the looped hand strap 11 in place.

The essence of the invention has to do with the dual purpose connecting and coupling means 18 which is characterized at the lower end by a tapering lag screw 20, has a machine threaded cylindrical stud 22 on its upper end and an outstanding endless flange 24 defining an appropriate limit stop shoulder which is employed as brought out in FIG. 2. With the parts properly assembled as illustrated in FIG. 2 it will be evident that the lag screw functions in the usual manner and that the upper stud-equipped end 22 is screwed into the fitting 40 to provide the desired connection and to support the camera in a readily usable and ready-to-aim position. The handgrip comes into play as suggested in FIG. 1 in that it is grasped with one hand. In practice the lower end (not shown) is pressed into the snow and the device then becomes a support for the photographic camera equipment illustrated in phantom lines in FIG. 1.

As pointed out the cap nut 42 is provided for the dual purposes of affording protection from the otherwise exposed threaded stud and is also used in conjunction with a conventional wrench (not shown) to drive the lag screw portion of the device into the shaft in a manner to secure the washer in place and to ready the device for use in mounting the camera in place. Utilization of the invention permits the skier to carry the photographic equipment at a continually controllable point while skiing and when in use provides him with a stable support simply by pressing the lower pointed end of the ski pole into the snow. When not in use the invention does not interfere with the normally functioning use of the ski pole. It will be evident therefore that the invention takes the place of the commonly used lag screw (not shown) and provides means atop the handgrip and shaft or pole for supporting the camera when the camera is attached in the manner suggested in FIG. 1.

It is believed that a careful consideration of the views of the drawing singly and collectively will enable the user to obtain a clear and comprehensive understanding of the subject matter of the invention, the manner in which the component parts are individually constructed and how they are assembled in ready-to-use relationship to achieve the result shown in advantage in FIG. 2. A more extended description is thought to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new as is follows:

- 10 1. In combination, a ski pole embodying a shaft having a lower end provided with the usual fixed guard and an upper end provided with a conventional-type molded handgrip having a complementary looped strap, mounting means accessibly and operatively mounted atop said handgrip for detachably mounting, transporting and supporting photographic camera equipment, whereby to thus permit said ski pole to be employed in the usual manner while skiing and also as a stabilizing and aiming support for the photographic camera equipment when using said equipment, said mounting means including an upstanding axially disposed machine-threaded stud expressly designed and adapted to be aligned with and retentively but removably screwed into a screw-threaded socket-like fitting provided in the bottom of the camera of said equipment, said stud being provided with a limit stop shoulder and below said shoulder with an integral lag screw which serves to position and hold said handgrip and companion strap in a given place on the upper end of said shaft, and a compressibly resilient washer surrounding an upper end of said lag screw and abutting said shoulder, said washer being aligned with and seated in a pocketing recess provided therefore in an adjacent end portion of said handgrip.
- 20 2. The combination defined in and according to claim 1, and a locknut screwed on said stud adjacent and abutting said shoulder and providing a retaining device for the bottom of said camera.
- 30 3. The combination defined in and according to claim 1, and a locknut screwed on said stud adjacent and abutting said shoulder and providing a retaining device for the bottom of said camera, said locknut comprising a flat-faced ring-like collar having a knurled peripheral surface.
- 40 4. The combination defined in and according to claim 2, and a cap nut removably screwed atop said stud and adapted for use as a protector for the otherwise exposed terminal end portion of said stud and also to accommodate a wrench as is used when screwing said lag screw into a screw-threaded socket provided therefor in an axial upper end portion of said shaft.
- 50 5. In combination, an upstanding pole including a shaft having upper and lower ends and a molded upstanding elongated handgrip provided with an upstanding downwardly and endwise outwardly opening blind cavity therein telescoped over the upper end of said shaft with the latter seated in said cavity, a looped strap having a first end passed laterally through one side of said handgrip and disposed between the upper end of the shaft and the opposing surfaces of said handgrip defining the inner end of said blind cavity, a lag screw secured through the upper end of said handgrip and threaded through said first end of the looped strap and into the upper end of said shaft, the upper end face of said handgrip including an outwardly opening recess surrounding said lag screw, a compressibly resilient washer disposed on said lag screw and seated in said re-

cess, said lag screw including a stop shoulder above said washer abutted against the latter, said lag screw above said shoulder including an integral upstanding machine screw-threaded shank having a locknut threadedly engaged therewith below the upper end of said shank, the upper end of said shank being adapted to be removably threaded in a screw-threaded fitting

provided on the bottom of camera equipment to be stationarily supported atop said pole.

6. The combination of claim 5 wherein said recess is outwardly concave and the axial face of said washer remote from said shoulder is compatibly convex.
